UNITED STATES PATENT OFFICE.

FRANK C. DORMENT, OF CLEVELAND, OHIO, ASSIGNOR TO THE VOLTO COMPANY, OF CLEVELAND, OHIO, A CORPORATION OF OHIO.

VOLATILIZER.

1,231,862.

Specification of Letters Patent.

Patented July 3, 1917.

Application filed December 30, 1916. Serial No. 139,988.

To all whom it may concern:

Be it known that I, FRANK C. DORMENT, a citizen of the United States of America, residing at Cleveland, in the county of Cuyahoga and State of Ohio, have invented certain new and useful Improvements in Volatilizers, of which the following is a specification, reference being had therein to the accompanying drawings.

This invention relates to a volatilizer that is preferably adapted for pocket use, is simple of construction whereby it may be readily cleansed and is positive and effective in operation.

This invention consists in the matters hereinafter set forth, and more particularly pointed out in the appended claim.

In the drawings,

Figure 1 is a view in longitudinal section through a volatilizer embodying features of the invention;

Fig. 2 is a view in section taken on or about line II—II of Fig. 1; and

Fig. 3 is a view in elevation, partly broken away, showing the device closed.

As herein shown, a medicament container 1, preferably cylindrical, or at least having a cylindrical interiorly screw-threaded mouth at the upper end, is permanently closed at the base by a bottom wall 2. A discharge cap 3 of suitable exterior contour for use as a nasal or oral piece, has an annular shoulder 4 above the screw-threaded portion 5 that engages into the mouth of the casing 1.

A lateral air inlet 6 below the shoulder 4 communicates with a depending air tube 7, the lower end of which is always at a slight interval above the bottom wall 2 of the casing. A discharge pipe 8, the lower end of which is intermediate the discharge end of the pipe 7 and the mouth of the casing, is secured in the cap in communication with a

discharge duct 9. A portion 10 of the cap periphery is knurled or chased as a ready grip.

As a result of this construction, a volatilizer is obtained that is readily sealed against accidental leakage through the air pipe by merely screwing down the mouth piece while the discharge opening because of the depending air outlet tube, does not permit the ready escape of the contents of the casing. The device is readily cleansed and is simple and effective in operation.

Obviously changes in the details of construction may be made without departing from the spirit of my invention and I do not care to limit myself to any particular form or arrangement of parts.

What I claim is:

A volatilizer comprising a medicament container permanently closed at the base, a cap with a longitudinal discharge duct therethrough and an air inlet, and in screw-threaded, adjustable engagement with the upper end portion of the container, the cap being adapted to seat against the upper end face of the container with the air inlet sealed by the container side, an air-inlet tube depending from the cap in communication with the air-inlet, and having the lower end thereof at a slight interval above the bottom of the container, and a short spray-pipe depending from the cap in communication with the discharge duct thereof and with the inlet end intermediate the cap and the lower end of the air-inlet tube.

In testimony whereof I affix my signature in the presence of two witnesses.

FRANK C. DORMENT.
